UNITED STATES PATENT OFFICE.

ADNIRAM J. COOK, OF WESTERLO, NEW YORK.

PIPE-JOINT.

1,267,313.

Specification of Letters Patent. Patented May 21, 1918.

Application filed August 20, 1917. Serial No. 127,320.

To all whom it may concern:

Be it known that I, ADNIRAM J. COOK, a citizen of the United States, residing at Westerlo, in the county of Albany and State 5 of New York, have invented certain new and useful Improvements in Pipe-Joints; and I do declare the following to be a full, clear, and exact description of the invention, such as will enable others skilled in the art 10 to which it appertains to make and use the same.

This invention relates to certain new and useful improvements in reinforced concrete conduits.

15 The primary object of the invention is to provide a reinforced concrete conduit, the sections of which are so constructed and fitted together as to effectively guard against leakage at the joint.

20 Another object of the invention is to provide a leak-proof pipe joint, the sections of which are similarly constructed so that any section may be joined to any other section.

25 A further object of the invention is to provide a simple and improved means for locking the adjacent sections of the conduit together.

30 A still further object of the invention is to generally improve upon the devices in this class by the provision of an extremely simple, strong, durable and comparatively inexpensive reinforcing and connecting element which is thoroughly efficient and reliable in operation, and well adapted to the 35 purpose for which it is designed.

With these and numerous other objects in view, the invention consists of certain novel features of construction, and the combination of parts as will be hereinafter fully 40 described and claimed.

In the accompanying drawings forming a part of the application, and in which similar reference characters are used to designate like parts throughout the several views:

45 Figure 1 is a sectional perspective view of one end of a conduit section constructed in accordance with this invention;

50 Fig. 2 is a longitudinal sectional view through a portion of my improved conduit, and showing the manner in which the abutting conduit sections are fitted and locked;

Fig. 3 is a detail perspective view of portions of the adjacent ends of the reinforcing and intermeshing cylinders or members,

illustrating more particularly the radially 55 flanged extensions of said cylinders; and

Fig. 4 is a plan view of portions of the adjacent ends of the reinforcing cylinders illustrating the manner in which the continuous band is disposed between the radial 60 flanges of the extensions of these cylinders.

Referring more particularly to the drawings, the numerals 1 represent two conduit sections, portions only of which are shown. These conduit sections 1 are molded or 65 otherwise made of reinforced concrete, and of tubular or cylindrical shape. It is, however, to be understood that they may be made in any other shape desired.

As more clearly shown in Fig. 2, two concrete conduit sections 1 are fitted together in axial alinement with one another, and each has one of its inner terminals 1^a contiguous to one of the inner terminals of the other of these sections. One end of each 70 conduit section is formed with an annular and outwardly tapering rib 2, adjacent to and extending axially beyond its inner terminal 1^a; an annular groove 3, the inner 75 wall of which is extended to form the outer annular surface of the rib 2; and an outer terminal 1^b, the latter lying in a radial plane cutting the axis of this conduit section at a point between the inner terminals 1^a of this section. The other end of each conduit 80 section is formed with an annular and outwardly tapering rib 2^a; an annular inwardly tapering groove 3^a disposed inwardly of the rib 2^a and outwardly of the 85 terminals 1^a; and an outer terminal 1^c disposed outwardly of the rib 2^a in a plane cutting the axis of the conduit between its inner 90 terminals 1^a, the inner wall of the groove 3^a being extended to form the outer annular surface of the rib 2^a.

95 Therefore, when the conduit sections are fitted together as shown in Fig. 2, the rib 2 fits in the groove 3^a, the rib 2^a fits in the groove 3, the inner terminals 1^a are contiguous to one another, and the outer terminals 1^b and 1^c are spaced from one another. The 100 structure thus far described is entirely of concrete or other cementitious substance.

The reference numeral 4 designates tubular reinforcing cylinders or tubular elements 105 which may be made of any suitable material, and which are preferably made of metal and provided with a great number of aper-

tures 5 therein. One of these elements 4 is embedded in each of the concrete sections 1. Projecting from the ends of each element 4 and beyond the terminals 1^a are spaced extensions 6, the free ends of which are bent laterally and outwardly as shown to form radial flanges 7. When the two conduits are fitted together, the hook shaped extensions of one section are interlapped 10 with those of the other sections, as clearly shown by Figs. 3 and 4.

When this has been done, a wire band 8 is encircled around the extensions 6, being disposed between the radial flanges 7 of the 15 two cylinders 4. The ends of the wire are twisted together in any suitable manner, and when this is done it will be seen that the conduit sections are firmly locked together.

20 The perforated or foraminous cylindrical elements 4 are terminated substantially at the outer terminals 1^b and 1^c, but their extensions 6 extend into the space between these outer terminals and at the inner ends 25 thereof, and these extensions 6 terminate in the radial flanges 7.

The space between the adjacent outer terminals 1^b and 1^c of the conduit sections is filled with a suitable filler 9 of mortar or 30 other cementing material. This may be applied in the plastic form before the conduit sections are brought together, or both before and after.

From the foregoing description taken in 35 connection with the accompanying drawings, the construction, use and operation of the device will be readily understood without a more extended explanation. It will be seen that the objects of the invention have been 40 effectively carried out as the double lap conduit joint and means for securing the two pipe sections together is such that leakage through the joint will be impossible.

It is obvious that various minor changes 45 in form, proportion, and in the minor details of construction may be resorted to without departing from the spirit of this invention, and hence it is to be understood that I do not wish to be limited to the construction herein shown and described other than as claimed.

Claims:

1. A cylindrical conduit section formed at one end with an inner terminal, an outer 55 terminal, an annular rib between the inner and outer terminals, and an annular groove between said rib and outer terminal, the said outer terminal being disposed in a radial plane cutting the cylinder's axis between said inner terminal and the opposite end of the conduit section; said opposite end being formed with an inner terminal, an outer terminal disposed in a radial plane cutting the axis between said inner terminals, an annular rib between the inner and outer terminals

of this end of the cylinder; and an annular groove between the last said annular rib and the inner terminal at this end of the conduit section, each of said annular grooves being of the correct size and shape to receive 70 such a rib as the one at the remote end of the conduit, and means extending beyond each outer terminal for coöperating with a similar means on a similar conduit section for securing these sections together while 75 one of the annular flanges of each conduit section is seated in one of the annular grooves of the adjoining conduit section.

2. A cylindrical conduit section formed at one end with an inner terminal, an outer terminal, an annular rib between the inner and outer terminals, and an annular groove between said rib and outer terminal, the said outer terminal being disposed in a radial plane cutting the cylinder's axis between said 80 inner terminal and the opposite end of the conduit section; said opposite end being formed with an inner terminal, an outer terminal disposed in a radial plane cutting the axis between said inner terminals, an annular rib between the inner and outer terminals of this end of the cylinder, and an annular groove between the last said annular rib and the inner terminal at this end of the conduit section, said annular ribs being tapered toward their outer or free ends, said 85 grooves being tapered inwardly and each adapted to receive one of such outwardly tapered ribs of a similar conduit section, and means extending from said outer terminals of each conduit section for coöperating with a similar means of said similar conduit section for holding one of the ribs of each section in one of the said grooves of 90 said similar section.

3. In a reinforcing and fastening element for a concrete conduit section, a foraminous hollow cylinder formed with spaced and axially parallel extensions at its ends, each of said extensions being formed with and terminating in a radially extending flange, the spaces between the said extensions being only sufficiently wide to receive an extension of a similar reinforcing and fastening element, for the purpose specified.

4. In a reinforced conduit section, a foraminous reinforcing and fastening element of hollow cylindrical form and having axially parallel extensions spaced from one another sufficiently to receive therebetween 110 the similar extensions of a similar reinforcing and fastening element, the free end of each of said extensions terminating in a radial flange, a cementitious cylindrical body 115 enveloping the foraminous part of said reinforcing and fastening element and extending through the foramina thereof and terminating substantially at the bases of said extensions, one end of said cementitious body being formed with an annular rib, the other 120

125

end of said cementitious body being formed with an annular groove adapted to receive an annular rib of a similar body and to fit snugly therein while the adjacent outer terminals of these bodies are spaced from one another and receive therebetween the radial flanges of the interlapped extensions of two of the said reinforcing and fastening elements, and an annular fastening element co-operating with the said radial flanges for 10 securing the conduit sections together.

In testimony whereof I have hereunto set my hand.

ADNIRAM J. COOK
